UNITED STATES PATENT OFFICE

95,851

DESIGN FOR A SWITCH CASING

Frederick Lobl, Middleboro, Mass.

Application April 25, 1935, Serial No. 56,553

Term of patent 14 years

To all whom it may concern:

Be it known that I, Frederick Lobl, a citizen of the United States, residing in Middleboro, in the county of Plymouth and State of Massachusetts, have invented a new, original, and ornamental Design for a Switch Casing, of which the following is a specification, reference being had to the accompanying drawing, forming part thereof.

Fig. 1 is a perspective view of the switch casing showing my new design.

Fig. 2 is a plan view of the front face of the switch casing.

Fig. 3 is a side elevation, Fig. 4 is an end view, and Fig. 5 is a plan view of the rear face of the switch casing.

I claim:

The ornamental design for a switch casing as shown.

FREDERICK LOBL.
